UNITED STATES PATENT OFFICE.

JOHN ISAAC THORNYCROFT, OF LONDON, ENGLAND.

WATER-TUBE BOILER.

SPECIFICATION forming part of Letters Patent No. 659,006, dated October 2, 1900.
Application filed July 6, 1899. Serial No. 722,923. (No model.)

To all whom it may concern:

Be it known that I, JOHN ISAAC THORNYCROFT, a subject of the Queen of Great Britain and Ireland, residing at Chiswick, London, in the county of Middlesex, England, have invented Improvements in Water-Tube Boilers, of which the following is a specification.

This invention has reference to water-tube boilers of the so-called "Daring" type, (see Thornycroft's patent, No. 452,401,) wherein, *inter alia*, an upper steam and water vessel is connected to three lower water vessels by groups of bent water-tubes so disposed that some of them form flues in which other tubes are located and through which the products of combustion escaping from the fire-boxes formed by and between the groups of tubes pass on their way to the chimney or uptake. In such boilers it sometimes happens, especially when they are of small height, that the hot gases are not uniformly distributed throughout the whole length of the flues, but tend to take a short path to the chimney, with the result that the whole of the heating-surface of the tubes is not utilized to the greatest advantage.

Now this invention has for its object to prevent or mitigate this drawback, for which purpose some of the tubes within each inner or outer flue or in each of the inner and outer flues are arranged to form, except at their ends, one or more close walls of tubes that serve to divide the flue lengthwise into two or more compartments that communicate with each other at their upper and lower ends through passages formed by and between the upper and lower end portions of the tubes after the manner of the inlet and outlet passages ordinarily formed between the upper and lower ends of the tubes constituting the inner and outer walls of the flue, the arrangement being such that hot gases on entering the lower end of the flue through the lower passages in that wall thereof which is next the fire-box will divide, a portion of them passing up the compartment of the flue next the fire-box and the remaining portion passing through the lower passages in the inter-

mediate close wall or walls of tubes and rising through the other compartment or compartments of the flue, the streams of hot gas upon reaching the upper ends of the compartments flowing through the passages left between the upper ends of the intermediate wall or walls of tubes and the inner or outer walls or inner and outer walls of the flues, according to the particular design of the boiler, and thence passing to the chimney. The height of the passages through the upper and lower portions of the intermediate close wall or walls of tubes can be varied to suit requirement. The height of the lower passages will usually be less than that of the lower passages in that wall of the corresponding flue which is next the fire-box. The invention can be applied in connection with various arrangements of water-tubes forming flues at one or at each side of the fire-box or each fire-box of the boiler.

The accompanying illustrative drawing shows in cross-section one arrangement of boiler of the kind referred to embodying the present invention.

The bent water-tubes that connect the upper steam and water vessel *a* to the lower central water vessel *b* enter the former vessel at each side thereof and are arranged in rows whereof the two inner rows *c d*—*i. e.*, those nearest to the vertical plane of the longitudinal center of the boiler—and the two outer rows *e f*—*i. e.*, those next to the fire-box—are bent to form, excepting as to their ends, tube-walls which constitute flues *g*, wherein the remaining tubes are arranged in rows, the two inner walls of the two flues *g* having between them a central space or flue *h*, in connection with a chimney *i* at the end of the boiler. Each of the outer lower water vessels *j* is connected with the upper vessel *a* also by several rows of tubes, whereof the two outer rows *k l* and the two inner rows *m m* are made to form (excepting as to the ends of the tubes) walls of a flue *o*, within which the remaining tubes of the group are arranged in rows. The outer wall of each inner flue *g* and the inner wall of each outer flue *o* meet at *p* at a suitable distance above

the fire-grate q , and the lower portions of the tubes constituting these respective walls are so arranged as to provide inlet-passages r between the wall-tubes, whereby products of combustion from each fire-box s can enter the respective flues g and o , up which they flow. The upper portions of the tubes c and d of both walls of each inner flue g and those m and n of the inner wall of each outer flue o are arranged to afford passages t between such portions of the said tubes whereby the upper ends of both flues g and o communicate with each other and with the central space or flue h .

15 Within each inner flue g , and also, it may be, as shown, within each outer flue o , is formed an intermediate close wall u of tubes, as and for the purpose hereinbefore described, the passages r in the lower portion of each such wall being usually of less height than the inlet-passages r in the adjacent wall of the flue, and the passages w in the upper portion of the said intermediate wall u being of about the same length, more or less, as those 20 —viz., t —in the upper portions of the flue-walls. As will be seen, the arrangement is such that the hot gases ascending the separate flues g and o of each fire-box s reunite at the top and thence flow through the upper 25 passages t of the inner walls of the inner flues g to the central space or flue h and thence to the chimney i . The upper steam and water vessel a is or may be connected to the lower central vessel b by downtake-tubes x , extending through the central space or flue h , and to the lower outer vessels j by separate external downtake-tubes y , as shown by dotted lines.

What I claim is—

40 1. In a water-tube boiler, an upper steam and water vessel, a lower water vessel, water-tubes connecting the two vessels and arranged to form a flue with openings for inlet and outlet of hot gases, and other water-tubes connecting said vessels and arranged within said flue so as to form, except at their ends, one or more close walls that divide said flue longitudinally into two or more compartments that communicate with each other at top and bottom, substantially as described for the purpose specified.

45 2. In a water-tube boiler, the combination of an upper steam and water vessel, a lower water vessel, and water-tubes so disposed that some of them form a flue in which other tubes are located, some of these latter tubes being arranged to form, except at their ends, one or more intermediate close walls that divide the flue lengthwise into two or more compartments that communicate with each other at their upper and lower ends through passages formed by and between the upper and lower end portions of the tubes forming said intermediate wall or walls; substantially as 55 described for the purpose specified.

3. In a water-tube boiler, an upper steam and water vessel, a lower water vessel, two fire-boxes, two groups of water-tubes connecting said vessels and located between said fire-boxes and arranged to form a central exit-flue between them, the tubes in each group being arranged to form two or more adjacent flues or flue-compartments that are each in communication at one end with the adjacent fire-box and at the other end with the central 70 flue, substantially as described.

4. In a water-tube boiler, an upper steam and water vessel, three lower water vessels, an uptake, water-tubes connecting said upper vessel to each of said lower vessels and arranged in four groups so as to form the sides of two fire-boxes, the tubes composing each inner group being arranged to form a flue having inlets and outlets for hot gases and in which other tubes of the group are located, 80 some of these latter tubes being arranged to form, except at their ends, one or more intermediate close walls which divide the flue lengthwise into two or more compartments that communicate with each other at their 85 upper and lower ends and also with the adjacent fire-box, and with said uptake, substantially as described.

5. In a water-tube boiler, an upper steam and water vessel, three lower water vessels, 95 an uptake, water-tubes connecting said upper vessel to each of said lower vessels and arranged in four groups so as to form the sides of two fire-boxes, the tubes of each group being arranged to form two or more adjacent 100 flues or flue-compartments that are each in communication at one end with the adjacent fire-box and at the other end with the uptake, substantially as described.

6. In a water-tube boiler, the combination 105 of an upper steam and water vessel, three lower water vessels, two inner and two outer groups of water-tubes connecting the upper vessel to the lower vessels and arranged to form a central exit-flue two fire-boxes and two inner and outer flues at the inner and outer sides of each fire-box being in communication with the fire-box at their lower ends and in communication with each other and with the central flue 110 at their upper ends, and an intermediate close wall of tubes arranged within each inner flue, so as to divide the same into two adjacent compartments that are in communication with each other at their upper and lower ends by 115 passages formed by and between the tube ends, substantially as described.

7. In a water-tube boiler, the combination of 120 an upper steam and water vessel, three lower water vessels, two inner and outer groups of water-tubes connecting the upper vessel to the lower vessels and arranged to form a central exit-flue two fire-boxes and two inner and outer flues, the inner and outer flues at the 125 inner and outer sides of each fire-box being 130

in communication with the fire-box at their lower ends and in communication with each other and with the central flue at their upper ends, and an intermediate close wall of tubes arranged within each inner and outer flue so as to divide each of such flues into two adjacent compartments that are in communication with each other at their upper and lower

ends by passages formed by and between the tube ends, substantially as described.

Signed at 77 Cornhill, in the city of London, England, this 15th day of June, 1899.

JOHN ISAAC THORNYCROFT.

Corrections in Letters Patent No. 659,006.

It is hereby certified that in Letters Patent No. 659,006, granted October 2, 1900, upon the application of John Isaac Thornycroft, of London, England, for an improvement in "Water-Tube Boilers," errors appear in the printed specification requiring correction, as follows: In line 125, page 2, before the word "outer" the word *two* should be inserted, and line 129, same page, before the word "outer," the first time it appears in the line, the word *two* should be inserted; and that the said Letters Patent should be read with these corrections therein that the same may conform to the record of the case in the Patent Office.

Signed, countersigned, and sealed this 6th day of November, A. D., 1900.
